UNITED STATES PATENT OFFICE.

EBENEZER A. W. JEFFERIES, OF PHILADELPHIA, PENNSYLVANIA, ASSIGNOR
TO WALTER WOOD, OF SAME PLACE.

HYDRAULIC SHEARS.

SPECIFICATION forming part of Letters Patent No. 552,710, dated January 7, 1896.

Application filed September 27, 1895. Serial No. 563,833. (No model.)

To all whom it may concern:

Be it known that I, EBENEZER A. W. JEFFERIES, a citizen of the United States, residing at the city of Philadelphia, in the county 5 of Philadelphia and State of Pennsylvania, have invented certain new and useful Improvements in Hydraulic Shears, of which the following is a specification.

My invention has relation to hydraulic shears; in which a movable knife is forced 10 against one connected with a fixed bed or anvil by hydraulic pressure; and it relates particularly to the means, controlled by a hydraulic cylinder or ram, whereby the movable 15 knife is forced down onto the fixed knife.

The principal objects of my present invention are, first, to provide in a hydraulic shears simple, durable, and efficient mechanism for forcing a movable knife against a fixed knife, 20 and, second, to provide in such a shears a knife-holder adapted to be operated by a wedge by means of a hydraulic ram or cylinder, the wedge not bearing directly upon the knife-holder, but upon a series of rollers interposed 25 between said wedge and knife-holder, whereby the latter may be quickly and easily moved in a downward direction against the fixed knife with little or no friction upon the actuating-wedge.

My invention, stated in general terms, 30 consists of hydraulic shears provided with mechanism for operating the movable knife-holder thereof against a fixed knife in substantially the manner hereinafter described and claimed.

The nature and scope of my invention will 35 be more fully understood from the following description, taken in connection with the accompanying drawings, forming part hereof, in which—

Figure 1 represents in front elevation hydraulic shears embodying features of my invention, and Fig. 2 is a transverse section on the line $x-x$ of Fig. 1.

Referring to the drawings, the frame or casting 40 for the shears consists of the standards $a-a$ and top or cap a' . Between the standards $a-a$ and at the bottom thereof is rigidly mounted a bed, anvil, or block b , to which the fixed 45 knife b' is suitably secured. The movable

knife d is secured to a head or frame e , the ends of which are guided in the standards $a-a$, so that the frame e and knife d may have a range of vertical movement therein. Between the lower edge of the cap a' and the upper edge of the knife-frame e is located a movable wedge f , which is guided in openings provided in the standards $a-a$. Between the wedge f and the upper edge of the knife-frame e are located a series of rollers h , which are secured to a connecting bar or rod h' , as indicated in the drawings. These rollers h by preference are flanged, as at h^2 , the wedge f and frame e resting on the rollers between the flanged sides thereof. Between the wedge f and the lower edge of the cap a' is placed a similar series of rollers k united with each other by means of a bar or rod k' . These rollers k are flanged, as at k^2 , in a similar manner as the rollers h , and as clearly indicated 70 in Fig. 2 of the drawings.

To counterbalance and raise the knife-frame an upright cylinder m is secured in the cap a' , the plunger or piston m' of which is connected by means of a cross-bar m^2 to one 75 end of the links m^3 , secured to the knife-frame e .

The wedge f is driven in one direction to depress the frame e and knife d by means of a hydraulic cylinder o , the plunger o' of which 80 is secured to the butt end of the wedge f . If desired, a returning-cylinder p , having its plunger p' secured to the small end of the wedge f , as illustrated in Fig. 1 of the drawings, may be used or the hydraulic cylinder 85 o may be provided with returning means.

In operation when the cylinder o is operated its plunger forces the wedge inward from right to left, the wedge moving upon the rollers h and k , the rollers having a slight range of 90 movement respectively upon the upper edge of the knife-frame e and the lower edge of the cap a' . The frame e and its knife d is thus slowly driven in a downward direction by the wedge and rollers until the knife d meets the 95 fixed or bed knife b' . By the arrangement thus described little or no friction is interposed in the path as well as movement of the wedge, owing to the fact that the wedge does not bear directly upon the frame e but upon 100

the rollers *h*, and does not bear against the cap *a* or other fixed part of the machine, but upon the rollers *k*.

The wedge *f* may be returned from left to right by means of the cylinder *p* or by any other preferred means, the knife-frame *e* being lifted as the wedge is returned by means of the counterbalancing-cylinder *m*.

Having thus described the nature and objects of my invention, what I claim as new, and desire to secure by Letters Patent, is—

1. In hydraulic shears, a casing provided with an anvil and fixed knife, a frame movable in said casing and provided with a knife, a transversely slideable wedge, two series of connected rollers, one series being interposed between the wedge and casing and the other between the wedge and knife frame, both series of rollers moving slightly in the same direction in which the wedge is slid, and means for actuating said wedge, substantially as and for the purposes described.

2. In hydraulic shears, a casing provided with an anvil and fixed knife, a frame movable in said casing and carrying a knife, a wedge adapted to be transversely slid to depress the knife frame, a series of rollers connected together and interposed between the wedge and knife frame, a series of rollers connected together and interposed between the casing and wedge, said two series of rollers traveling slightly in the same direction in which the wedge is slid, means for operating said wedge and means adapted to counterbalance said knife frame and to return the same when not depressed by the wedge, substantially as and for the purposes described.

In testimony whereof I have hereunto set my signature in the presence of two subscribing witnesses.

EBENEZER A. W. JEFFERIES.
